SHEET HOLDER

Bruce K. Slonberger, Dayton, Ohio, assignor to
 The National Cash Register Company, Dayton,
 Ohio, a corporation of Maryland

Application October 1, 1949, Serial No. 119,124

4 Claims. (Cl. 281—44)

1

This invention relates to a holder for supporting a stack of forms on which written entries are to be made.

The object of the invention is to provide a holder for a stack of business forms, said holder comprising an end formed to resiliently hold the stack of forms thereon, a tear-off means for easy removal of a form from the stack, a hand rest to assist the user in making entries at the bottom of the form, and a notch to provide easy access to the hand rest.

With this and incidental objects in view, the invention includes certain novel features of construction and combinations of parts, a preferred form or embodiment of which is hereinafter described with reference to the drawing which accompanies and forms a part of this specification.

In the drawing:

Fig. 1 is a top view of the form holder showing the hand rest in normal position in full lines, and in an extended position in chain lines.

Fig. 2 is a side view of the form holder and indicates a stack of forms thereon in chain lines.

Fig. 3 is a sectional view, taken on line 3—3 of Fig. 1.

General description

The form holder described herein is used in retail stores, restaurants, filling stations, or any establishment where written records are to be made. For example, the holder can be used by a waitress in a restaurant in writing a guest's order for food. In taking orders in such establishments, the waitress must usually hold a stack of guest checks in one hand while making the entries thereon, and, when entries are to be made near the bottom of a check, it is difficult to make legible entries, since the waitress has no rest for her writing hand. The invention herein provides a novel adjustable hand rest for such contingencies, which can be moved out of the way when an order has been entered on a check. The holder is also provided with a "tear-off" means for quick removal of the check from the stack. The hand rest is made easily accessible for movement into a desired position by providing a notch in the main support thereof through which the thumb or a finger can pass to firmly grasp the hand rest. A stop on the hand rest limits the return movement of the hand rest, so that it is always in accessible position for adjustment.

The holder is preferably made of a metal which is sturdy, yet light in weight, such as aluminum, although it is not intended to limit the invention to such material.

Detailed description

The holder is provided with a main supporting member 10, of a size slightly wider than a stack of checks to be supported thereby, and long enough to extend beyond the lower ends of the

2

stack of checks. A stack of checks 11 is indicated in Figs. 1 and 2 by chain lines to indicate the size of the stack of checks in relation to the length of the main supporting member 10.

The forward end of the main supporting member 10 is bent at right angles to form a wall 12 extending across the full width of the member 10. Formed on the wall 12 is a rearwardly-extending section 13, bent downwardly at a slight angle, and the terminal of said section is bent to form a short surface 14 substantially parallel with the face of the main supporting member 10. The rear edge 15 of the surface 14 provides a "tear-off" means for easy removal of a check from the stack. The section 13 is spring-biased in the direction of the face of the main supporting member 10, so as to provide a firm grip on the stack of checks 11.

A slideable hand rest 16 is provided with turned-in flanges 17 at each side thereof, which flanges are formed to slidably fit the sides of the main supporting member 10. If desired, the flange 17 can be formed to provide space for a tally sheet, which can be supported on the hand rest 16, beneath the main supporting member 10, in such a way that the tally sheet is accessible for entries when the hand rest is moved into accessible position.

A flange 18 is formed on the rear end of the hand rest for the dual purpose of making the hand rest more rigid and for providing a stop for the hand rest when it is moved into the position shown in Figs. 1 and 2, in which position the inner wall of the flange formation 18 strikes the rear edge of the main supporting member 10.

To render the hand rest 16 easily accessible for moving it into a desired hand rest position, the main supporting member 10 is provided with a notch 19, which can be of any shape but which is illustrated herein as a semicircular notch. The notch 19 provides a clearance for the waitress's thumb or finger through which the hand rest can be firmly grasped for sliding the hand rest into a desired position.

The holder is not necessarily limited in construction for holding a stack of forms, since the extensible hand rest is also useful in systems where only one printed form is clipped to the holder at one time.

While the form of the invention shown and described herein is admirably adapted to fulfill the object primarily stated, it is to be understood that it is not intended to confine the invention to the one form or embodiment shown herein, for it is susceptible of embodiment in various other forms.

What is claimed is:

1. In a device of the class described, the combination of a supporting member for a stack of business forms on which hand-written records

are to be made, said member consisting of a flat plate having one end thereof formed to provide means to hold one end of the stack of business forms on the upper face of the flat plate, and an adjustable hand rest slidably mounted on the under face of the flat plate.

2. In a device of the class described, the combination of a supporting member for a stack of business forms on which hand-written records are to be made, said member consisting of a flat plate having three unformed edges and one edge formed to provide means to hold one end of the stack of business forms on the top face of the flat plate, an adjustable hand rest located in the under face of the flat plate, and grooves formed on the sides of the hand rest engageable with two of the unformed edges of the flat plate to form a slidable engagement therebetween.

3. In a device of the class described, the combination of a supporting member for a stack of business forms upon which written entries are to be made, said supporting member comprising a flat plate having three unformed edges and one formed edge, said formed edge providing a receptacle to receive one end of a stack of said forms on the top side of said plate, said receptacle comprising a first section of said flat plate formed upwardly at right angles to the face of said flat plate, and a second section formed rearwardly on said first section, said second section being biased downwardly toward the face of said member to form a resilient means to releasably hold the stack of forms on the holder; and a hand rest slidably mounted on the underside of the flat plate to provide an adjustable hand rest when making written entries on the forms.

4. In a device of the class described, the combination of a supporting member for a stack of business forms upon which written entries are to

be made, said supporting member comprising a flat plate having three unformed edges thereon and one formed edge, said formed edge providing a receptacle to receive one end of a stack of said forms, one side of said receptacle comprising a first section of said flat plate formed upwardly at right angles to the face of said flat plate, and a second section formed rearwardly on said first section, said second section being biased downwardly toward the face of said member to form a resilient means to releasably hold the stack of forms in the said receptacle; and a hand rest slidably mounted on the under side of said flat plate to provide an adjustable hand rest when making written entries on the forms, said hand rest provided with runways formed to slidably engage two of the unformed sides of said member whereby the stack of forms is located on one side of the flat plate and the hand rest is located on the opposite side of the flat plate to render each accessible independently of the other.

BRUCE K. SLONNEGER.
